WELDING GLOVE

Robert Bakke, Minneapolis, Minn., assignor of
one-half to Gudrun Elizabeth Swahn, Minne-
apolis, Minn.

Application June 25, 1943, Serial No. 492,238

2 Claims. (Cl. 2—161)

This invention relates to new and useful improvements in welding gloves in general.

It is well known that welding gloves are subjected to extremely rough and hard usage and particularly to flying sparks and particles of molten metal which may quickly render a glove useless. Various attempts have heretofore been made to provide a welding glove capable of protecting the hand against intense heat, but to the best of my knowledge none of these devices have proven entirely satisfactory, as their backs are not impervious to damage from flying sparks and particles of molten metal. Such a device, is disclosed in the patent to L. J. Sabin, #2,044,105, the back of which is composed of an outer or secondary soft pliable back cover of leather and an inner heat breaker which cooperate to protect the back of the hand against intense heat.

I have found from actual experience that the use of a soft pliable material in the back of a welding glove does not entirely serve the purpose because flying sparks and particles of molten metal frequently embed themselves in the back thereof and may quickly burn a hole thru the back of the glove.

After considerable experimental work I discovered that a welding glove may be rendered substantially entirely fireproof and impervious to flying sparks and particles of molten metal by embodying in the back of the glove a relatively stiff fireproof shield constructed of a material which has a relatively hard smooth surface, whereby when sparks and particles of molten metal strike the surface thereof, they will quickly "bounce" off, as they cannot become embedded therein.

It is therefore an object of the present invention to provide an improved welding glove comprising a relatively stiff fireproof back shield which overlies the entire back of the glove, whereby flying sparks striking the back of the glove are not likely to adhere thereto.

A further object is to provide in a welding glove comprising the usual back, palm and cuff portions, a relatively stiff fireproof shield overlying the entire back portion of the glove and secured thereto along the sides of the glove, and a shield of similar material being fitted over the cuff or gauntlet portion of the glove to provide a protection therefore against flying sparks and particles of molten metal.

Other objects of the invention reside in the novel shape of the back shield whereby it completely covers the back of the glove and offers a protection to the tips of the fingers; in the pro-

tection of the cuff shield and its association with the back shield, whereby flying sparks and particles of molten metal are not likely to contact the back of the glove at the wrist; and in the manner of embodying the back and cuff shields in the glove whereby such operation may readily be accomplished by conventional manufacturing operations.

Other objects of the invention will appear from the following description and the accompanying drawing and will be pointed out in the annexed claims.

In the accompanying drawing there has been disclosed a structure designed to carry out the various objects of the invention, but it is to be understood that the invention is not confined to the exact features shown, as various changes may be made within the scope of the claims which follow.

20 In the drawing:

Figure 1 is a view of a welding glove showing the invention embodied therein;

Figure 2 is a view looking at the face or palm of the glove;

25 Figure 3 is a back view of the glove;

Figure 4 is an enlarged detail sectional view on the line 4—4 of Figure 2;

Figure 5 is a detail sectional view on the line 5—5 of Figure 1; and

30 Figure 6 is a detail sectional view on the line 6—6 of Figure 3.

In the selected embodiment of the invention herein disclosed, there is illustrated in Figures 1 and 2, for purposes of disclosure, a welding glove comprising the usual cuff portion 2 and back and palm portions 3 and 4, respectively, stitched together in the usual manner to provide the hand and cuff portions of the glove.

An important feature of the present invention resides in the provision of means for protecting the back of the glove against flying sparks and particles of molten metal, frequently encountered when performing welding operations.

To thus protect the back of the glove a relatively stiff fireproof shield, generally designated by the numeral 5, is secured to the glove along the side seams 6 and 7, as shown in Figure 4, whereby the intermediate or central portion of the shield is unattached to the glove so that air may circulate between the glove back 3 and the shield 5.

The front end portion 8 of the glove preferably extends well beyond the finger tips, as shown in Figures 1 and 2, and is bent downwardly as

shown at 8 as in Figure 1 to provide greater protection for the tips of the fingers.

The rear portion 9 of the back shield 5 extends rearwardly over a portion of the cuff 2 of the glove wrist. By reference to Figure 1, it will be noted that the shield has a side portion 11 which fits down over the side of the glove and partially overlies the crotch 12 of the glove, thereby to protect this portion of the glove from sparks and flying embers. The portion 11 of the glove is secured to the cuff portion of the glove by an interned seam 13, best shown in Figure 5.

To further protect the glove against damage by flying sparks and particles of molten metal, the usual cuff portion or gauntlet 2 of the glove is provided with a relatively stiff fireproof shield 14, which preferably is made of a material similar to the material from which the back shield 5 is made. The cuff shield 14 may be fitted over the usual cuff or gauntlet 2 of the glove, and is shown secured to the wrist portion of the glove by a row of stitches 15 which it will be noted, are shown passing thru the rearwardly turned flange portion 16 of a heat-resisting lining 17 of the cuff portion of the glove, as will be understood by reference to Figure 1.

The cuff shield 14 is preferably made from a single blank cut to be fitted over the cuff or gauntlet 2 of the glove and having its opposed edges stitched together along one side of the glove by a seam 18, shown in Figures 3 and 6.

As an added protection to the hand against intense heat, such as is frequently encountered when welding, a heat-resisting member 19 is interposed between the back shield 5 and the back of the glove, as will be understood by reference to Figures 1 and 4. The heat-resisting member 19 may be constructed of any suitable material capable of resisting heat as, for example, asbestos. The member 19 may be secured to the body of the glove along the sides thereof by the seams 6 and 7, shown in Figures 1, 2 and 4.

The novel welding glove herein disclosed has been found very practical in actual operation. One of the important features of the glove resides in the stiffness of the back and cuff shields 5 and 14, respectively, and in the smooth hard surface thereof. By so constructing these shields, sparks and particles of molten metal which may impinge thereagainst, will "bounce" off the shields, usually without leaving a mark thereon. The back shield offers complete protection for the back of the glove, as it extends well down over the sides of the back of the glove, and forwardly beyond the finger tips. It also extends rearwardly over the adjacent portion of the cuff shield 14, thereby to prevent sparks and particles of molten metal from getting under the shield 5 from the rear edge portion thereof. It will also be noted that the fore and little fingers of the glove do not have their fore ends attached to the back shield 5, nor the heat resisting member 19, whereby the fingers of the hand may be freely used in a conventional manner, and whereby provision of the fireproof back shield 5 and cuff shield 14 will not in any way interfere with the operator's work.

Both the back shield 5 and heat resisting member 19 have their central portion unattached to the glove back, whereby air may circulate be-

tween said members lengthwise of the glove, when the hand is opened and closed.

Gloves embodying the invention herein disclosed have been used for long periods of time without damage thereto by flying sparks and particles of molten metal, which has resulted in a reduction in the cost of performing welding operations, as well as the maintenance cost of equipment, such as gloves. It is not uncommon when using conventional welding gloves that the utility of such gloves may be rendered useless for further wear after a few hours work, particularly when they are constantly subjected to flying sparks, as is frequently the case. The novel glove herein disclosed is not affected by sparks or particles of molten metal, as such sparks quickly bounce off the surface of the shields when striking them whereby no damage is done to the glove.

The stiff material, preferably asbestos, used in the construction of the back shield 5 serves another purpose in that it provides a very substantial support for the welding torch or tool. When welding, the left hand is usually held in substantially the position shown in Figure 2, whereby the torch may be supported upon the rounded upper edge of the shield 5, as will readily be understood.

It will be apparent to those skilled in the art that I have accomplished at least the principal objects of my invention, and it will also be apparent to those skilled in the art that the embodiments herein described may be variously changed and modified without departing from the spirit of the invention, and that the invention is capable of uses and has advantages not herein specifically described; hence it will be appreciated that the herein disclosed embodiments are illustrative only, and that my invention is not limited thereto.

40 I claim as my invention:

1. In a welder's glove comprising the usual back, palm and cuff portions, a preformed, non-bendable fireproof shield overlying the back of the glove and extending forwardly beyond the finger tips and rearwardly over a portion of the cuff and attached to the sides of the glove and free from the outer sides of the fore and fourth fingers, whereby all of the operator's fingers are always free to carry on the necessary work, the intermediate portion of said shield being unattached, and a fireproof shield of similar material fitting over the entire cuff portion of the glove and cooperating with said back shield to protect the wearer's hand against sparks and molten particles of metal.

2. In a welder's glove, comprising the usual back, palm and cuff portions, a preformed substantially non-flexible fireproof shield having portions of its side edges secured to the sides of the glove in alignment with the palm portion thereof, and free from the outer sides of the fore and first fingers, whereby said shield will not impede the operation of any of the operator's fingers when using the glove, and the forward end of said shield extending well beyond the tips of the fingers and curving inwardly to provide a protective covering therefore against sparks and bits of molten metal which may fly from the work during a welding operation.

ROBERT BAKKE
